UNITED STATES PATENT OFFICE

2,592,033

POCKET HANDKERCHIEF

Burton G. Hicks, South Easton, Mass.

Application October 22, 1948, Serial No. 55,903

5 Claims. (Cl. 2-279)

1

This invention relates to a simulated pocket handkerchief of the display type adapted to be worn in the breast pocket of an outer coat or similar garment and has for its primary object to construct a sturdier and improved device of the foregoing type, achieving in such construction a reduction in time, labor and cost but without sacrificing any of the utility, practicalness and merit of the device and without detracting from the ornamental or display formation thereof.

Another important object of this invention is to provide a simulated display handkerchief that is preformed and constructed with a holder for insertion in the breast pocket of a coat or suit; that will necessitate no folding or refolding after its original construction; that will be neat in appearance and will not bulge outwardly when inserted in a pocket that will consequently obviate any bulky pocket appearance.

Another important object of this invention is to provide a simulated pocket handkerchief including a piece of prefolded material, of a pattern and color complimentary to various patterned and colored suits and ties, means being provided for securely holding and retaining the prefolded and joined pieces of material in a compact, folded position and for enabling the same to be unitarily and easily inserted in a pocket and retained therein with the upper portions of the material protruding above the upper edge of the pocket.

These and ancillary objects and structural features of merit are attained by this invention, a preferred embodiment of which is set forth in the following description and illustrated in the accompanying drawings, wherein:

Figure 1 is a fragmentary perspective view of a coat or similar outer garment, having a breast pocket, within which is inserted and retained, a simulated display handkerchief constructed in accordance with the principles of this invention;

Figure 2 is a plan view of the handkerchief and holding means therefor;

Figure 3 is a plan view of the holder;

Figure 4 is a vertical sectional view taken on line 4-4 of Figure 2;

Figure 5 is a transverse sectional view taken on line 5-5 of Figure 2;

Figures 6, 7 and 8 are plan views of the handkerchief per se or material strips for the device of the instant invention, illustrating the same in its various stages of construction or formation.

Referring now more particularly to the drawings, there is shown the components of the instant invention generally designated by the character reference 10, the same being brought together in a manner as taught hereinafter and

2

for a purpose to produce a compact, neat and attractive simulated display handkerchief.

In carrying out this invention, attention is first directed to Figures 6-8, wherein the preferred form and type of pieces of material, constituting the main portion of the device, are illustrated. It is to be noted, with reference to Figure 6, that there is provided a pair of triangular pieces, or sections, of material 12 and 14 which are seamed at their edges as at 16 and 18. The triangular piece 14 is substantially larger than the section 12 and is superimposed thereon, the pieces being joined by in and out stitching 20 and 22, running vertically on the pieces.

In Figure 7, a second section 24 is shown the same comprising a pair of triangular sections or pieces of material, corresponding in design and color to the sections 12 and 14. The pieces 26 and 28 of the section 24 are preferably of a scalene triangular formation, all of the pieces being of an acute angle formation. The pieces 26 and 28 are provided with hems 30 on their longitudinally extending side edges converging towards the minor point. The joined pieces 12 and 14 are superimposed on the section 24, as seen in Figure 8, so that the minor ends, or corners, 32, 34, 36 and 38 are displayed in staggered relationship. As will be seen in Figure 8, the display corners 32, 38 of the sections 12, 14 define the area of the display corner 34 of the section 28 and said corner 34 together with the corner 38 of section 12 define the area of the display corner 36 of section 26.

Attention is now directed to Figure 3 of the drawings, wherein there is shown a holder 40 constructed from a solid piece or sheet of suitable material, such as paper, plastic, or composition. The holder comprises a central section 42 having a transversely extending crease or fold line 44 disposed therethrough. The central section 42 is defined by a pair of arcuate opposed side edges 46 and 48, at the outer ends of which are formed end sections 50 and 52.

The end section 52 is formed with a cut-out portion 54 defined by a transverse cut line 56 and a pair of arcuately formed longitudinally extending opposed end cut extensions 58 and 60. Thus, the cut-out portion 54 constitutes a flap or tab open at three sides and integral at its lower end with the end section. Spaced inwardly from the arcuate sides of the cut-out portion 54 are a pair of arcuate slits 62 and 64. The end section 52 terminates in a semi-circular or arcuate end 66, having a series of rearwardly spaced arcuate score or crease lines 68. The end section 50 is substantially rectangular in form and is provided with a pair of extending tabs or arms 70 and 72, being formed with transverse crease or fold lines 74 and 76 at their attached ends.

In carrying out the construction of the simulated display handkerchief, the pieces of mate-

rial, shown in Figure 8, are superimposed on the central portion or body portion 42 of the holder, with their points or minor ends extending longitudinally above the transverse score line 44. The base portions of the pieces of material are inserted on the end section 52, between the arcuate side edges 58 and 60 of the cut-out portion or tab 54, so that the cut-out portion 54 engages upon the front portion or face of the sections. It is to be noted that the ends of the pieces of material will project substantially in lateral fashion beyond the outer side edges of the end section 52 and will be folded about the side edges and superimposed on the back portion of the end section. At this time, the center section 42 will be turned down at the score line 44 extending transversely therethrough at its center point so that the end section 50 will be superimposed upon the ends of the material pieces or sections disposed about the back portion of the end 52. The arms or tabs 70 and 72 will then be brought around the side edges of the end 52 and inserted within the slits 62 and 64, so that the end section 50 serves to clamp upon the extending ends of the pieces of material and hold the base portions of the material within the cut-out portion 54.

As seen in Figures 2-5, suitable means may be provided for fastening and securing the arms 70 and 72 within the slits, so as to prevent the same from accidental withdrawal and to securely hold the material sections on the holder. In this respect, staples 78 may be provided and may be easily secured, so as to penetrate through the holder sections and through the material pieces and join the same unitarily. Of course, if desired, the upper portion of the section 24 may be stapled, as at 80 to the central portion of the holder.

The arcuate or semi-circular end 66 of the end section 52 of the holder is adapted to be slid downwardly in a pocket, preferably the breast pocket 82 of a coat or outer garment or similar article of apparel 84. The particular formation and design of the end will enable the holder and pieces of material held and retained thereon to be easily inserted in the pocket and to rest securely therein, without producing or causing an outward bulge or unsightly appearance. When the end is seated on the inner closed end of the pocket, the sections of material will protrude above the upper edge of the pocket, as seen in Figure 1. It is to be noted that the end 66 is provided with arcuate crease or fold lines, so that the same may be adjusted for various heights in the pocket, either by bending the material back upon itself or by cutting the lower portions of the material away, on the score lines, whichever is desired.

Thus, it can be appreciated that there is provided a novel simulated display handkerchief, utilizing a holder formed of a stiff material that will resist bending, after it has been constructed and will retain the portions or pieces of material in their neatly folded position. It can be appreciated that the holder will be formed of the proper length to fit snugly within conventional pockets but the score lines may be utilized and bent or the end portions of the holder removed, so that the lower end of the holder may be slid easily into a pocket, without causing the holder to bend and the holder may be retained easily in the pocket, allowing the upper ends of the material to protrude slightly above the upper edge of the pocket.

However, while one embodiment of this inven-

tion has been shown, it is to be understood that certain other embodiments can be carried out, as coming within the spirit and scope of the appended claims.

Having described the invention, what is claimed as new is:

1. A handkerchief display device for insertion in a coat pocket including a holder of foldable material comprising handkerchief supporting and retaining end sections, respectively, and an intermediate section with arcuate side edges folded centrally downwardly and rearwardly of said supporting section to provide an upwardly tapering handkerchief backing portion on said supporting section and to dispose the retaining section back of said supporting section, a simulated handkerchief traversing said supporting section and tapered portion in front thereof and embodying a straight base, upwardly pointing corners, and end portions folded rearwardly in between said supporting and retaining sections, means on said supporting section supporting said handkerchief by its base with said corners above the fold of said intermediate section, and means on said retaining section folded forwardly over the folds of said end portions of the handkerchief and attached to said supporting section to hold the handkerchief in place.

2. A handkerchief display device according to claim 1 wherein said first-named means comprises an upstanding flap on said supporting section.

3. A handkerchief display device according to claim 1 wherein said first-named means comprises an upstanding flap on said supporting section, and said second-named means comprises arms stapled to said supporting section and overlapping said flap to hold the flap in place.

4. A holder for insertion in a coat pocket to display a simulated handkerchief, said holder being of foldable material and including handkerchief supporting and retaining end sections, respectively, and an intermediate section with arcuate side edges folded centrally downwardly and rearwardly with respect to said supporting section to provide an upwardly tapering handkerchief backing portion on said supporting section and to dispose said retaining section back of said supporting section, means on said supporting section adapted to support the handkerchief upright with said tapered portion backing the handkerchief and ends of the handkerchief folded backwardly in between said end sections, and means on said retaining section foldable forwardly over said supporting section and attached thereto and adapted to fold over the folds of said handkerchief ends to retain said handkerchief in place.

5. A holder according to claim 4 wherein said first-named means comprises a flap over which said second-named means is folded to overlap the same and retain said flap in place.

BURTON G. HICKS.
